RETURN BEND

Frederick E. Key, St. Louis, Mo., assignor to Key Company, East St. Louis, Ill., a corporation of Missouri

Application March 15, 1935, Serial No. 11,276

3 Claims. (Cl. 122—360)

This invention relates to return bends forming passages between the ends of tubes in oil stills which are subjected to very high temperatures and very high pressures.

5 An object of the invention is to provide a return bend adapted to be attached to the adjacent ends of adjacent tubes and having a passage communicating with passages opening laterally from the tubes, the parts of the return bend being constructed and arranged so that they will withstand the very high temperatures and very high pressures to which they are subjected when in use and will, at the same time, maintain leak-proof joints.

15 Another object of the invention is to provide an improved return bend having openings in alignment with the tubes to which the return bend is attached and removable seals for said openings which, when in service, maintain leak-proof joints and which may be removed without detaching the return bend from the tubes to permit the tubes to be cleaned.

Another object of the invention is to provide an improved return bend having means in connection therewith for locating the parts in proper relative relationship to form a passage from one tube to the other.

Other objects of the invention will be readily apparent from the following description, reference being made to the annexed drawings, in which—

Fig. 1 is an outer end elevation of one embodiment of the invention.

Fig. 2 is a side elevation.

35 Fig. 3 is a view looking toward one of the edges of the device that is shown in Fig. 2.

Fig. 4 is a longitudinal sectional view of the return bend.

Fig. 5 is a sectional view approximately on the 40 line 5—5 of Fig. 4.

Fig. 6 is a sectional view on the line 6—6 of Fig. 4.

Fig. 7 is an outer end elevation of a variation of the invention.

45 Fig. 8 is a side elevation of the return bend that is shown in Fig. 7.

Fig. 9 is a view looking toward one of the edges of the device that is shown in Fig. 8.

Fig. 10 is a longitudinal sectional view of the 50 return bend shown in Figs. 7, 8, and 9.

Fig. 11 is a sectional view approximately on the line 11—11 of Fig. 10.

Fig. 12 is a sectional view on the line 12—12 of Fig. 10.

55 Fig. 13 is a view partly in section and partly

in elevation of another embodiment of the invention.

Fig. 14 is a sectional view on the line 14—14 of Fig. 13.

Fig. 15 is a sectional view on the line 15—15 of Fig. 13.

Fig. 16 illustrates a device for removing the closure plug from the end of the return bend.

In the form of the invention shown in Figs. 1 to 5, inclusive, a tubular section 1 is attached to each of the still tubes 2. Each section 1 is screwed on the end of a tube 2 after which the ends of the tubes are rolled or expanded into internal grooves 3 in the sections 1, thus providing a rigid attachment and a leak-proof joint. The 15 inside diameter of the sections 1 is the same as the inside diameter of the tubes 2. Each of the sections 1 has a laterally extended lug 4 and beyond the lugs 4 each of said sections 1 is formed with a lateral radially inclined opening 5.

A connecting member 6 has a pair of spaced 20 openings through which the tubular sections 1 extend, the peripheral surfaces of the sections 1 and the inner walls of said openings through the members 6 being smoothly ground to provide leak-proof joints. The member 6 has an opening 7 through the central part thereof, the ends of which are in communication and registration with the respective openings 5 when the member 6 is fitted on the tubular sections 1. Each of the tubular sections 1 has a tapered portion 8 fitting in correspondingly tapered portions 9 of the openings through the member 6 to locate the sections 1 and the member 6 in proper position in which the opening 7 has its ends in communication with the respective openings 5. The connecting member 6 is formed with a pair of spaced flanges 10 between which the lugs 4 extend. Thus, the lugs 4 cooperate with the flanges 10 to bring the 30 passages 5 and 7 in communication with each other when the parts are assembled and to prevent the tubes from twisting.

The outer ends of the tubular sections 1 are threaded and a sleeve 11 is screwed on each of said sections. A tapered sealing gland 12 extends 45 into a tapered recess 13 in the outer portion of the member 6 around each tubular section 1. Each gland 12 is formed with an externally threaded circumferential flange 14 on its outer end against which the sleeves 11 are screwed 50 to force the glands 12 into the tapered recesses 13 and into tight sealing engagement with the walls of said recesses and the peripheral walls of the sections 1 to form a leak-proof joint.

The outer end of each section 1 is formed 55

with an annular groove 15 in which a sealing ring 16 is seated. A plug 17 is extended into the outer end of each section 1 and has a circumferential flange 18 provided with a groove 19 receiving the outer end or edge of the corresponding ring 16. The outer wall 20 of the flange 18 is curved and a correspondingly shaped sealing ring 21 is mounted on the wall 20 and clamped thereon by a nut 22 screwed into the outer end of the sleeve 11. Thus, the outer end of each tubular section 1 is provided with a leak-proof closure that will withstand the high pressures and the high temperatures to which the device is subjected. The outer end of each plug 17 beyond the nut 22 includes a head 23 adapted to be engaged by the fork 24 of a detaching tool 25 (Fig. 16). The detaching tool 25 has a collar 26 rigid thereon and inwardly from said collar a plunger 27, which may be driven against the collar 26 to loosen or withdraw the plug 17 when the nut 22 is loosened.

After the sleeve 11 is removed, an internally threaded member of conventional construction may be screwed on the threaded flange 14 and against the outer end of the member 6 to withdraw the gland 12 from the socket 13.

The sleeves 11 have holes 28 through which any leakage may drain and through which the sealing rings 16 may be observed and inspected.

30 In the construction shown in Figs. 7 to 12, inclusive, the walls of the still tubes 29 are relatively very thick in comparison with the inside diameter of said tubes to withstand very high pressures and very high temperatures. The tubes 29 have conical shoulders 30 thereon which telescope into correspondingly tapered openings 31 in a connecting member 32. The tubes 29 have a number of divergent radially inclined holes 33, the outer ends of which open into 40 grooves 34 in the connecting member 32, and said grooves open into a transverse opening 35 in the intermediate part of the connecting member. Thus, a communicating passage from one tube to the other is provided.

45 The outer ends of the tubes 29 are externally threaded beyond the connecting member 32 and are sealed by devices like the devices that seal the outer ends of the tubular sections 1, and similar parts have the same reference numerals 50 applied thereto.

In the construction shown in Figs. 13, 14, and 55 15, the tubes 36 have radially inclined holes 37 opening into grooves 38 in the connecting member 39, which is provided with a transverse opening 40 constituting a communication from one tube 36 to the other. Conical shoulders 41 on the tubes 36 fit in correspondingly shaped openings through the connecting member 39 and provide a leak-proof joint. The outer ends of 60 the tubes 36 are externally threaded beyond the connecting member 39. A gland 42 is mounted on each tube 36 and extends into a tapered socket 43 and is pressed into sealing engagement with the wall of the socket and the wall of the

5 tube by a sleeve 44 that is screwed on the end of each tube 36 and against the corresponding gland 42. The inner ends of the sleeve nuts 44 are split and after being screwed to position against the gland 42 are clamped by bolts 45 and nuts 46 applied in the manner shown. Each gland 42 has a circumferential flange 47 on its outer end provided with a number of threaded holes 48 through which releasing screws 49 may be screwed into abutting contact with the outer end of the connecting member 39 to withdraw and force the glands 42 from the sockets 43 after the sleeve nuts 44 have been removed.

10 The elements that close the outer ends of the tubes 36 are the same as the elements that close the outer ends of the tubular sections 1 and like reference numerals are applied to corresponding parts.

15 This return bend will withstand the very high temperatures and very high pressures to which it is subjected when in use. The construction and arrangement of the elements may be varied in other particulars than those specifically illustrated and described without departure from the 20 nature and principle of the invention.

25 I claim:—

1. A return bend for establishing communication between two tubes each having a plurality of inclined openings through the wall thereof comprising a connecting member telescoped on said tubes and having internal grooves in communication with said openings through the walls of said tubes and a transverse passage between said grooves, and means for holding said connecting member in proper position.

30 2. A return bend for establishing communication between two tubes each of which has an opening through the wall thereof for the passage of fluid, comprising an integral connecting member telescoped on said tubes and having a transverse opening in communication with said openings through the walls of said tubes, a sealing gland on each tube extending into the outer end of the adjacent portion of said connecting member and forming a tight joint between said tube and said connecting member, and a closure for the outer end of each tube having a part thereof 35 screwed on said tube and engaging the outer end of the adjacent gland.

40 3. A return bend for establishing communication between two tubes each of which has a number of openings through the wall thereof for the passage of fluid, comprising a connecting member telescoped on said tubes and having a transverse passage therethrough and having internal grooves in communication with said passage and with all of said openings in the respective tubes, and clamping means mounted on said tubes holding said connecting member in rigid location on said tubes and forming a leak-proof joint between said connecting member and said tubes.
